UNITED STATES PATENT OFFICE.

RAY F. AGNEW, OF CLEVELAND, OHIO, ASSIGNOR TO AGNEW ELECTRIC WELDING COMPANY, OF DETROIT, MICHIGAN, A CORPORATION OF MICHIGAN.

ELECTRICAL TRANSFORMER.

1,160,357.

Specification of Letters Patent.

Patented Nov. 16, 1915.

Application filed March 3, 1909. Serial No. 481,172.

To all whom it may concern:

Be it known that I, RAY F. AGNEW, a citizen of the United States, resident of Cleveland, county of Cuyahoga, and State of Ohio, have invented a new and useful Improvement in Electrical Transformers, of which the following is a specification, the principle of the invention being herein explained and the best mode in which I have 5 contemplated applying that principle, so as to distinguish it from other inventions.

My invention relates to electrical transformers, and particularly to that class of transformers designed to furnish currents of 15 large volume such as are required for heating and working metals.

In the usual types of transformers designed for the purpose mentioned, it is impossible to dispose of the turns of the secondary in a manner such as to intersect and occupy more than a comparatively small portion of the magnetic field of the primary coil, unless such secondary be a cast metal structure. Inasmuch as such cast metal is 25 of a conductivity only about one-half that of wrought metal, and inasmuch as the absence of the laminated structure in such cast metal construction makes it practically impossible to obtain the cooling surface required in order to obtain the most efficient and economical results, it has been usually found inexpedient to employ such cast metal structures in devices of this character. Wrought metal laminated structures are 30 therefore generally used, notwithstanding that the same occupy, as before indicated, only a comparatively small portion of the magnetic field of the primary coil, and notwithstanding the consequent loss of current resulting therefrom and the decrease in the efficiency arising out of such loss.

The object of my invention is to combine the advantages of a cast metal construction in so far as pertains to occupying the greatest 45 possible part of the magnetic field, with the advantages of a laminated wrought metal construction, in so far as pertains to the latter's increased conductivity and the presence therein of a large cooling surface to 50 avoid excessive heating; and at the same time provide for convenient attachment of the carriages or workholders of welding machines to the terminals of the secondary so as to permit of the required range of move-

ment of such carriages or workholders. My 55 said object, in addition to the provision of the characteristics above mentioned, also includes the provision of a structure which shall present economy of construction and maintenance to the greatest possible degree. 60

The annexed drawing and the following description set forth in detail a specific structure embodying my invention, the disclosed structure, however, constituting but 65 one of various forms in which the principle of the invention may be applied.

In said annexed drawing:—Figure 1 is a section of a transformer embodying my invention taken upon a plane passing through the axis of the core, and showing the secondary in elevation. Fig. 2 is an elevation of such transformer as viewed from the direction indicated by the arrow in Fig. 1. Fig. 3 is a plan of such transformer. Fig. 4 is a detail perspective of one of the strips or 75 ribbons of conducting material which go to make up the secondary of the transformer.

Referring to the drawing, A is a hollow core constructed in the usual manner, of flat plates of iron or steel, piled upon each other and suitably secured to form the usual laminated structure required. Disposed at opposite sides of and surrounding said core are two primary coils B and B', whose ends b b' b' are preferably located in the same 80 planes respectively. These coils are connected with each other in series, as shown in the drawing, or they may be connected in the circuit in multiple, as will be readily understood. 90

Located in the magnetic field of the primary coils is the secondary C. This secondary is a laminated conductor consisting of a plurality of thin flat strips or ribbons of metal, usually copper, which are continuous and unbroken from one terminal c to the other terminal c'. These strips or ribbons are piled one upon another and occupy a position parallel with and close to the ends b b' of the primary coils. 95

One part C' of the secondary lies in the field of one of the coils B' of the primary and the other part C² lies in the field of the other primary coil B as shown. Each part C' C² consists of two turns (c² c³ and c⁴ 105 and c⁵) at opposite ends of the coils joined at the top by a bridge portion, (c⁶ c⁷). The said turns are opposite the ends b b' of the

primary coils and the strips or ribbons are placed so that their faces lie in planes parallel with the direction of such turns and parallel with the ends of the coils B B', said turns being thereby placed edgewise around the core. To obtain this construction with the flat ribbon material, the latter is caused to pass from the terminal portion *c* downwardly in the inside of the core and parallel with the one face *b'* of the one coil B and along its entire depth. It is then folded or doubled at right angles upon itself and passes along the entire width of the coil, as shown. It is then again folded or doubled upon itself and passes upwardly on the outside of the core and parallel with the same coil end. One turn is thus formed. The material then doubles upon itself at right angles as shown in Fig. 3 and then passes along parallel with the upper side of the coil to form the bridge portion *c'*. From thence, it again doubles and passes over to the opposite end *b* and on the inside of the core downwardly along and parallel with said end. At the lower part of this end of the coil it then turns at right angles across the coil end, as shown in dotted lines in Fig. 3, to the outside of the core. From this point it passes upwardly on the outside of the core parallel with this coil end, thus completing a second turn. It now turns at right angles and passes over to a point opposite the end *b* of the other primary coil B. Passing downwardly inside the core along and parallel with this coil end it turns and passes beneath the core to the outside thereof, upwardly to form a third turn, along the upper side of the coil to form the bridge portion *c'*, then over to the opposite end *b'* of the coil downwardly along and parallel with such end, across and beneath the core, then upwardly parallel with and along the same coil end to complete the fourth turn, the upper portion of this last part of the secondary forming the terminal *c'*. This terminal portion is bent at right angles and then upon itself and again at right angles so that its faces occupy planes lying at right angles with respect to the planes in which the faces of the terminal portions *c* are located.

The terminals are secured in any suitable and well known manner to the carriages or workholders. By constructing the terminal portions as above described, it will be noted that each is flexible in one direction only and that these directions are different from each other, and as shown, at right angles relatively to each other. By these means, the one carriage or workholder may be adjustable or movable in one direction, and the other carriage or workholder may be adjustable or movable in a direction at right angles to the direction of movement of the first named carriage.

65. Having fully described my invention, what

I claim and desire to secure by Letter Patent is:—

1. In a transformer, the combination with a core and primary windings, of a secondary including a turn composed of a laminated conductor, consisting of a plurality of flat strips edgewise wound about the core for the major portion of the turn, the flat faces of the strips being arranged in planes parallel to the plane of the direction of the primary winding.

2. In a transformer, the combination with a core and primary windings, of a secondary including a plurality of turns each composed of a laminated conductor consisting of flat strips or ribbons edgewise wound about the core for the major portion of the turn, the flat faces of the strips being arranged in planes parallel to the plane of the direction of the primary winding.

3. In a transformer the combination with a core and a primary coil, of a secondary consisting of a laminated metal structure formed of a plurality of flat strips or ribbons arranged in turns around the core, the flat faces of the major portions of such turns being arranged in planes transverse to the core.

4. In a transformer, the combination with a core and a primary coil, of a secondary consisting of a plurality of flat metal strips folded at right angles to form turns, the strips being edgewise wound around the core for the major portion of the turn and having a section formed at an angle to the edge wound portions to connect the turns in electrical series.

5. In a transformer, the combination of two primary coils, a suitable core lying in the field of such coils; and a secondary composed of two connected parts and comprising a plurality of flat strips or ribbons of conducting material, each strip being continuous and unbroken and forming part of each secondary coil; each part of the secondary including turns whose faces are in planes parallel with the plane of the direction of the primary windings.

6. In a transformer, the combination with a core and the primary windings, of a secondary comprising two parts each divided into two sections, each section being opposite one of the two opposite ends of the primary coil, and each having a turn consisting of a plurality of flat strips or ribbons of conducting material whose faces lie in planes parallel with the side edges of said primary coil.

7. In a transformer, the combination with a core and a primary coil, of a secondary coil comprised of a flat strip or ribbon, having straight portions at opposite sides of the core, respectively parallel and adjacent to opposite sides of the primary coil, and a straight portion connecting the same paral-

lel and adjacent to a face of the primary coil which is transverse with said sides thereof.

8. In a transformer, the combination with a core and a primary winding, of a secondary consisting of a comparatively thin wide flat strip of bendable material, the flat faces of the major portion of the strip being parallel and adjacent to those faces of the primary coil which are transverse to the core.

9. In a transformer, the combination with a core and primary windings; of a secondary, consisting of a comparatively thin wide flat strip of bendable material having portions positioned upon opposite sides of said primary windings, with the flat faces of the strip parallel to the plane of the direction of the primary windings, and a connection between the portions of the strip upon opposite sides of said primary windings.

10. In a transformer, the combination

with the core and primary windings; of a secondary, consisting of U-shaped members positioned upon opposite sides of said primary windings, each of said members being formed of a comparatively thin wide flat strip of bendable material, having the flat faces parallel to the plane of the direction of said primary windings, and a connection between said U-shaped members.

11. In a transformer, the combination with a core and a primary coil, of a secondary coil comprised of a flat strip or ribbon having straight portions at opposite sides of the core, and a straight portion connecting the same, the three said portions being parallel and adjacent to the same face of the primary coil.

Signed by me, this 1st day of March, 1909.

RAY F. AGNEW.
